UNITED STATES PATENT OFFICE.

ALBERT CWOJNA, OF CARNEGIE, PENNSYLVANIA.

RAILWAY-SWITCH.

1,388,700.

Specification of Letters Patent. Patented Aug. 23, 1921.

Application filed May 5, 1921. Serial No. 466,953.

To all whom it may concern:

Be it known that I, ALBERT CWOJNA, a citizen of the United States of America, residing at Carnegie, in the county of Allegheny and State of Pennsylvania, have invented certain new and useful Improvements in Railway-Switches, of which the following is a specification.

This invention relates to certain new and useful improvements in railway switches and has particular reference to that type of switch wherein the rail sections of a switch are bodily moved for alining the switch rail sections with stationary rail sections.

The primary object of the invention resides in the provision of a railway switch wherein a plate having the switch rail sections secured thereto is bodily shiftable transversely of the track for alining the different rail points with the stationary rail sections.

With the above general objects in view and others that will become apparent as the nature of the invention is better understood, the same consists in the novel form, combination and arrangement of parts hereinafter more fully described and shown in the accompanying drawings, in which like reference characters designate corresponding parts throughout the several views.

In the drawings,

Figure 1 is a top plan view of a railway switch constructed in accordance with the present invention showing the switch rail sections fixedly secured to a transversely shiftable plate,

Fig. 2 is a cross sectional view taken on line II—II of Fig. 1 showing the switch rail sections secured to a transversely shiftable plate with the lever arm and link for shifting the plate,

Fig. 3 is a longitudinal sectional view taken on line III—III of Fig. 1 showing the transversely shiftable plate anchored to the mounting base plate therefor,

Fig. 4 is a detail sectional view taken on line IV—IV of Fig. 1 showing the switch rail sections anchored to the shiftable plate,

Fig. 5 is a perspective view of the mounting base plate, and

Fig. 6 is a perspective view of the shiftable switch point supporting plate and a portion of the operating link.

Referring more in detail to the accompanying drawings and particularly to Fig. 1,

there is illustrated a portion of a railway track wherein a supporting tie 1 has longitudinal track rails 2 secured thereto, a spaced supporting tie 3 having rails 4 alined with the rails 2 and switch rails 5 supported on the tie 3 at the usual divergence of switch rails.

The switch rail sections are interposed between the rails 2 and 4—5, and are supported on a transversely shiftable plate for alining either pairs of switch rail sections with the rails 2—4, or 2—5. Supporting ties 6 interposed between the ties 1 and 3 have mounted thereon the base plate 7 shown in detail in Fig. 5 as provided with upwardly directed offset end extensions 8 resting on the ties 6 and secured thereto by suitable bolts as indicated at 9, the offset extensions 8 being cut away intermediate their ends as at 10 to accommodate the fastening bolts 9. As shown in Fig. 1, the adjacent ends of the rails 2, 4, and 5 are anchored to the ties 6.

The supporting plate 11 shown in detail in Fig. 6 carries upon the lower face thereof, a pair of longitudinally extending cleats 12 that are received in elongated openings 12^a formed in the base plate 7, the openings 12^a being of greater length than the cleats to provide for a sliding movement of the plate 7, this movement being limited by the ends of the cleats engaging the end walls of the openings 12^a. To anchor the switch supporting plate 11 to the base plate 7 for sliding movement relative thereto, and against upward movement transverse strips 13 underlying the base plate 7 are secured by bolts 14 to the cleats 12, this connection permitting a free sliding movement of the plate 11 relative to the base plate 7 but preventing a separating movement thereof, this latter construction being clearly shown in Figs. 2 and 3.

The switch rails embody parallel sections 15 adapted for alining with the track rails 2 and 4 and parallel diverging sections 16 adapted for alining with the track rails 2 and 5, the switch rails 15 and 16 being anchored to the plate 11 by bolts 17 passing through openings 18 in the plate 11 and carrying nuts 19 or other retaining devices for engaging the base flanges of the switch rails 15 and 16.

To shift the plate 11 transversely of the track, and upon the base plate 7, a link rod 20 has one end pivotally connected to a lug 21 carried by the bottom face of the plate 11

and extending through a slotted opening 21^a in the base plate 7 with the free end of the link rod sliding through an opening provided in the bar 22 secured between the supporting ties 6 as clearly shown in Figs. 1 and 2. A bell crank 23 pivoted as at 24 has one end thereof provided with a slotted opening 25 for receiving a pin 26 projecting upwardly from the link rod 20 while the other end of the bell crank 23 has an operating rod 27 attached thereto.

In the operation of the device, assuming that the switch points upon the plate 11 are in the position shown in Fig. 1, with the switch rails 15 alined with the track rails 2 and 4, and it being desired to aline the switch rails 16 with the track rails 2 and 5, the rod 77 is operated to shift the bell crank 23 and link rod 20 to move the plate 11 upon the base plate 7, thereby bodily shifting the switch supporting plate to aline the switch rails 16 with the track rails 2 and 5, the movement being limited by the ends of the cleats 12 engaging the end walls of the slotted openings 12^a, it being noted that the plate 11 is limited in its movements in opposite directions by the coöperating cleats and openings. Any perpendicular movement of the plate 11 relative to the base plate 7 is eliminated by the strips 13 secured to the cleats 12 and underlying the base plate 7 as shown in Figs. 2 and 3.

While there is herein shown and described the preferred embodiment of the invention, it is nevertheless to be understood that minor changes may be made without departing from the spirit and scope of the invention as herein claimed.

What is claimed as new is:

40 1. A railway switch of the type described comprising in combination with fixed rail sections, a rigidly mounted base plate, a switch rail supporting plate slidably mounted on the base plate and adapted to bodily move the switch rails for alining with the fixed rail sections and coöperating means carried by the base plate and switch rail supporting plate for limiting the movement of the switch rail supporting plate, said means including elongated openings formed in the base plate and cleats carried by the other plate received in said openings and of less length than said openings.

55 2. A railway switch of the type described comprising in combination with fixed rail sections, a rigidly mounted base plate, a switch rail supporting plate slidably mounted on the base plate and adapted to bodily move the switch rails for alining with the fixed rail sections and coöperating means carried by the base plate and switch rail supporting plate for limiting the movement of the switch rail supporting plate, said means including elongated openings formed in the base plate and cleats carried by the other

plate received in said openings and of less length than said openings and means carried by said switch rail supporting plate coöperating with the base plate to prevent perpendicular movement of the switch rail supporting plate relative to the base plate. 70

3. A railway switch of the type described comprising in combination with fixed rail sections, a rigidly mounted base plate, a switch rail supporting plate slidably mounted on the base plate and adapted to bodily move the switch points for alining with the fixed rail sections and coöperating means carried by the base plate and switch rail supporting plate for limiting the movement of the switch rail supporting plate, said means including elongated openings formed in the base plate, cleats carried by the other plate received in said openings and of less length than said openings, means carried by said switch rail supporting plate coöperating with the base plate to prevent perpendicular movement of the switch rail supporting plate relative to the base plate and means for shifting the switch rail supporting plate. 80

4. A railway switch of the type described comprising in combination with fixed rail sections, a rigidly mounted base plate, a switch rail supporting plate slidably mounted on the base plate and adapted to bodily move the switch rails for alining with the fixed rail sections and coöperating means carried by the base plate and switch rail supporting plate for limiting the movement of the switch rail supporting plate, said means including elongated openings formed in the base plate and cleats carried by the other plate received in said openings and of less length than said openings, means carried by said switch rail supporting plate coöperating with the base plate to prevent perpendicular movement of the switch rail supporting plate relative to the base plate, a link rod attached to the switch rail supporting plate and a bell crank associated with said link rod for shifting the same and the plate with the switch rails carried thereby. 100

5. A railway switch of the type described comprising in combination with fixed rail sections, a rigidly mounted base plate, a switch rail supporting plate slidably mounted on the base plate and adapted to bodily move the switch rails for alining with the fixed rail sections, coöperating means carried by the base plate and switch rail supporting plate for limiting the movement of the switch rail supporting plate, said means including elongated openings formed in the base plate, cleats carried by the other plate received in said openings and of less length than said openings, means carried by said switch rail supporting plate coöperating with the base plate to prevent perpendicular movement of the switch rail supporting plate relative to the base plate, said base 115
